UNITED STATES PATENT OFFICE.

MICHAEL PETROCCHI, OF GRAND RAPIDS, MICHIGAN, ASSIGNOR TO ROSE LABEL MACHINE CO., OF GRAND RAPIDS, MICHIGAN.

SEWING-MACHINE FOR SPECIAL WORK.

1,198,574. Specification of Letters Patent. Patented Sept. 19, 1916.

Application filed December 12, 1912; Serial No. 736,257.

To all whom it may concern:

Be it known that I, MICHAEL PETROCCHI, a citizen of the United States, residing at Grand Rapids, Michigan, have invented certain new and useful Improvements in Sewing-Machines for Special Work, of which the following is a specification:

This invention relates to improvements in sewing machines for special work.

10 It relates especially to improved guiding and feed means for the work, where such work is the attaching of labels, the stitching on of patches for any purpose, or the stitching on of pockets, or stitching for reinforcements, or the like.

15 The invention may be incorporated into the machine in the first place, or it may be provided as an attachment for existing machines, as it does not have to do with the special features of the stitching but merely the proper holding and feeding of the work.

20 The objects of the invention are to provide a simple and effective means for feeding a presser foot or work holder of a sewing machine.

25 Objects relating to economies of construction and details of operation will definitely appear from the description to follow.

30 I accomplish the objects of my invention by the devices and means described in the following specification.

35 The invention is clearly defined and pointed out in the claims.

40 A structure constituting a preferred embodiment of my invention is clearly illustrated in the accompanying drawing, forming a part of this specification, in which:

45 Figure I is a perspective view of a sewing machine embodying my invention. Fig. II is an enlarged plan view of the structure of my improvement when provided as an attachment. Fig. III is a detail transverse sectional elevation taken on line 3—3 of Fig. II. Fig. IV is a detail sectional elevation taken on line 4—4 of Fig. II. Fig. V is an inverted plan view of the head for the carrying arm for the presser foot or work holder.

50 Fig. VI is an inverted plan view of the central guide block. Fig. VII is a transverse detail sectional view on line 7—7 of Fig. VI. Fig. VIII is a detail transverse sectional elevation of the lower main guide plate, taken on a line corresponding to line 3—3 of Fig. II. Fig. IX is a detail plan

55 view of a modification of the carrier head

and guide means for attaching diamond shaped labels. Fig. X is a second modification, showing a diagrammatic view of the carrier head and guide means for attaching labels which are beveled at one end only. Fig. XI is a detail plan view of a third modification of the carrier head and guide means for attaching labels in which one side of the label is curved.

60 In the drawings, the sectional views are taken looking in the direction of the little arrows at the ends of the section lines, and similar numerals of reference refer to similar parts throughout the several views.

65 Considering the numbered parts of the drawing, the base 1, the arm 2 and the head 3 of the sewing machine are in the usual form, and the machine is provided with a suitable work plate 4 of any required size provided with a carefully smoothed surface.

70 On the base 1 of the machine is disposed my improved guide structure, the main or base guide plate 5 being secured on the base 1 of the machine. A suitable carrier head is driven and guided within this structure in a rectangular path and carries the carrying arm 6 for the spring pressure foot arm 7, which is hinged at 8. A tension spring 9 is provided for holding this arm downwardly in position.

75 A presser foot or work holder 10 is provided for carrying and delivering the work properly to the needle of the sewing machine. The presser foot or work holder shown is the presser foot made use of by Arthur Rosenthal in his improved sewing machine, for which he applied for Letters Patent of the United States under date of March 11, 1912, Ser. No. 683,068, and is not a part of my invention.

80 My invention is applicable to such work holder, or any other, or a button hole presser foot, or any kind of work holder.

85 The guide mechanism is driven by ratchet wheel 11, which is acted upon by ratchet pawl 12, which pawl 12 is controlled from the arm 13 connected thereto by the link 14. The arm 13 is connected to any rock shaft or reciprocating part of the sewing machine. A detent 15 is provided to coöperate with the actuating pawl 12.

90 The presser foot is raised by the pull-rod 16, which is connected by suitable means, see dotted lines, to the lift-rod 17, all clearly appearing in Fig. I. As my invention does not relate to the driving means or to the

presser foot or work holder and the various parts just enumerated, I have not deemed it necessary to describe the same fully in detail. My invention relates to the proper 5 actuation and guiding of the carrier head which controls the carrying arm 6, which carries the spring pressed arm 7. To this end a guiding base plate 5 is provided on the base of the machine and secured there- 10 to preferably by screws. On this base plate is suitably guided the carrier head 19, which is retained in position thereon by the top plate 18. A vertical shaft 20 is journaled in the plate 18 and bottom plate 5 and is 15 driven by the ratchet wheel 11 already referred to. The driving pinion 28 is on this shaft.

The carrier head 19 is provided with a 20 downwardly-projecting flange 19^a forming an inverted rectangular box on the under side of the same, which serves as a guiding means. This box is provided with suitable slots 19^b at front and rear, and at 19^c at the sides to permit the passage of the guiding pins 28 hereinafter described. This 25 head 19 is rectangular in form, and is engaged or stopped by and then guided within the lateral guiding flanges 21, 21 at each side, and 22, 22 at the front and rear of the base plate, the object of the structure being to carry the same around the four sides of a rectangle in order to impart that motion to the presser foot or work holder 10 by the carrying arm therefor.

30 Within the rectangular box 19 formed by the downwardly projecting flange 19^a is the central rectangular guide block 27, having a central rectangular aperture and provided on its under side with lateral guide ribs 25 which engage in suitable transverse guide ways 24 formed in the plate 5. This rectangular guide block 27 is of such width as to admit the proper backward and forward movement of the carrier head 19, which is 40 effectively guided from front to rear by the close engagement with this head.

Upwardly-projecting guide or stop pins 23 are provided, which engage and pass through the slots 19^b and 19^c, respectively, 50 to permit proper movement of the carrier head 19 and insure its being properly guided into position. The carrier head 19 is provided with an internal rectangular rack and is disposed to be actuated by the pinion 28 55 carried by the shaft 20. The racks 29 at front and rear, and end racks 30—30 are driven from the pinion, and the motion of the said carrier head corresponds to the size of the label which is to be attached, or the 60 size of the work to be done by the sewing machine.

I have thus described fully all the parts of my improved structure, and it will be noted that the carrier head is guided by 65 parallel guides on both sides and is very

closely engaged in whichever direction it may be moved. The driving means is centrally located between the two parallel guides so that the parts move very freely without binding and consequently secure the 70 desired results with a minimum friction.

While I have described my main structure as adapted to rectangular work, and while that will be the usual form, I desire to state that labels of different form and different 75 forms of stitching can be applied, the work holder being suitably conformed and the parts guided. I have indicated in Fig. IX a diamond form, in Fig. X a four-sided figure with one side beveled, and in Fig. XI 80 a four-sided figure with one side curved. From a consideration of these illustrations, it is clear that a great variety of forms can be worked out. Such forms, however, are all practically quadrangular. It is of great 85 importance that the carrier head be maintained in successive parallel positions, and the disposition of the guides in these various structures secures that result, the forms of the various guides being parallel, or designed to secure parallel action, although the guides themselves are of straight or curved lines, giving the predetermined form to the stitching and the movement.

While it is of consequence that the rack 95 is centrally disposed of the guides with this structure, it would be possible to dispose the rack otherwise, as the tendency of the guide members to bind is very slight and the structure would not work so freely, but that 100 would be the only objection to the different arrangements.

While I have shown the teeth of the rack formed completely into the corner of the rectangular portion, it is, of course, understood that the teeth in the extreme corner are of no consequence as they do not mesh with the pinion. I will state that the internal guide and the external guide in this structure coöperate completely and effectively together, each limiting the motion of the other and thereby securing the very best result and the complete avoidance of any binding so that the action of the sewing machine is in no way interfered with.

I have shown the structure in its preferred form, and it secures great efficiency in the operation of the structure. The rack is effectively guided so that the meshing with the driving pinion is perfect, and as the 120 movement is always rectilinear it is perfectly even and very effective to control and secure even length of stitches entirely around any label or patch that it is desired to stitch.

As before intimated, the structure may be driven by any suitable means. I have shown a simple ratchet, such as is made use of in the structure appearing in the patent application of Rosenthal already referred to. 125 130

My improvement relates particularly to the guide means for controlling the guiding head which carries the presser foot or work holder. The guides shown are double and parallel and coöperate effectively with the driving means. The structure is thus very stanch and effective. Single guides transverse to each other might be used if constructed with care and provided with effective stops.

I desire to claim my invention in the specific form shown and also broadly as pointed out in the appended claims.

Having thus described my invention, what I claim as new and desire to secure by Letters Patent is:

1. In a special work sewing machine having a suitable base, the combination of a work holder or presser foot; a main guide base disposed upon the base of said sewing machine, having upwardly-projecting guide flanges disposed rectangularly about the same; suitable guide pins disposed upon the said guide base; a carrier head for traveling in the said guide base, and having downwardly-projecting guide flanges therearound containing slots to pass said guide pins and forming guide ways therefor; a central guide block disposed in the space within the downwardly-projecting guide flanges of said head and of less dimensions in one direction than said flanged space to permit movement of said head thereon, and provided with downwardly-projecting guides engaging suitable guide ways formed in the guide base to permit movement of said block transversely to the movement of the head thereon; a centrally disposed vertical shaft with a pinion thereon; means connected to a moving part of the sewing machine to impart motion thereto; an internal toothed rectangular rack centrally disposed of the said carrier head and adapted to mesh with and be driven by the pinion on the said vertical shaft; and an arm on said carrier head to carry said work holder or presser foot, all coacting substantially as described for the purpose specified.

2. In a special work sewing machine having a suitable base, the combination of a work holder or presser foot; a main guide base disposed upon the base of said sewing machine, having upwardly-projecting guide flanges disposed rectangularly about the same; suitable guide pins disposed upon the said guide base; a carrier head for traveling in the said guide base, rectangular in form, of such dimensions as to permit the required movement thereof in a rectangular path when guided within the guides of the main guide base, and having downwardly-projecting guide flanges therearound containing

slots to pass said guide pins and forming guide ways therefor; a centrally disposed vertical shaft with a pinion thereon; means connected to a moving part of the sewing machine to impart motion thereto; an internal toothed rectangular rack centrally disposed of the said carrier head and adapted to mesh with and be driven by the pinion on the said vertical shaft; and an arm on said carrier head to carry said work holder or presser foot, all coacting substantially as described for the purpose specified.

3. In a special work sewing machine having a suitable base, the combination of a work holder or presser foot; a main guide base disposed upon the base of said sewing machine; suitable guide pins disposed upon the said guide base; a carrier head for traveling in the said guide base, and having downwardly-projecting guide flanges containing slots to pass said guide pins and forming guide ways therefor; a central guide block disposed in the space within the downwardly-projecting guide flanges of said head and of less dimensions in one direction only than said flanged space to permit movement of said head thereon, and provided with downwardly-projecting guides engaging suitable guide ways formed in the guide base to permit movement of said block transversely to the movement of the head thereon; a centrally disposed vertical shaft with a pinion thereon; means connected to a moving part of the sewing machine to impart motion thereto; an internal toothed rectangular rack centrally disposed of the said carrier head and adapted to mesh with and be driven by the pinion on the said vertical shaft; and an arm on said carrier head to carry said work holder or presser foot, all coacting substantially as described for the purpose specified.

4. In a special work sewing machine having a suitable base, the combination of a work holder or presser foot; a main guide base disposed upon the base of said sewing machine having upwardly-projecting guide flanges disposed rectangularly about the same; a carrier head for traveling in the said guide base, rectangular in form, of such dimension as to permit the required movement thereof in a rectangular path; guide means to direct said carrier head in a rectangular path; a vertical shaft with driving pinion thereon; an internal toothed rectangular rack centrally disposed of the said carrier head and adapted to mesh with and be driven by the pinion on the said vertical shaft; and an arm on said carrier head to carry the work holder or presser foot, all coacting substantially as described and for the purpose specified.

5. In a special work sewing machine having a suitable base, the combination of a work holder or presser foot; a main guide

base disposed upon the base of said sewing machine; a carrier head for traveling in the said guide base, rectangular in form and having downwardly-projecting guide flanges 5 therearound containing slots; a central guide block disposed within the downwardly-projecting flanges and of less dimensions in one direction only than said flanged space suitably guided on said base; a centrally disposed vertical shaft with a pinion 10 thereon; means connected to a moving part of the sewing machine to impart motion thereto; an internal toothed rectangular rack centrally disposed of the said carrier 15 head and adapted to mesh with and be driven by the pinion on the said vertical shaft; suitable guide pins disposed upon the said guide base for engaging the said carrier head and coöperating with the slots in 20 the flanges thereof; and an arm on said carrier head to carry the work holder or presser foot, all coacting substantially as described and for the purpose specified.

6. In a special work sewing machine having a suitable base, the combination of a 25 work holder or presser foot; a main guide base disposed upon the base of said sewing machine; a carrier head for traveling in the said guide base, rectangular in form with 30 downwardly projecting flanges; a central guide block disposed within the space embraced by said downwardly-projecting flanges and of less dimensions in one direction only than said flanged space, suitably 35 guided on said base; a centrally-disposed vertical shaft with a pinion thereon; means connected to a moving part of the sewing machine to impart motion thereto; an internal toothed rectangular rack centrally 40 disposed of the said carrier head and adapted to mesh with and be driven by the pinion on the said vertical shaft; and an arm on said carrier head to carry the work holder or presser foot, all coacting substantially 45 as described and for the purpose specified.

7. In a special sewing machine having a suitable base, the combination of a work holder or presser foot; a main guide base disposed on the base of said sewing 50 machine; a carrier head carried by the said guide base; a plurality of guide means disposed transversely to each other to maintain said carrier head in parallel position when in motion; a rectangular rack cen-

trally disposed on said carrier head; a pinion 55 disposed to coact with the rack to drive said carrier head; suitable guides forming an inclosed path, independent of said rack and pinion, and means to positively direct the carrier head in a rectangular course; 60 and a carrying arm on said carrier head for carrying the work holder or presser foot, coacting for the purpose specified.

8. In a special work sewing machine having a suitable base, the combination of a 65 work holder or presser foot; a main guide base disposed on the base of said sewing machine; a carrier head; guide means disposed transversely to each other to maintain said head in parallel position when in motion; 70 an internal toothed gear rack disposed on the said head of a form corresponding to the form desired to be stitched; a pinion disposed to coact with the rack to drive the said carrier head; guide means comprising 75 an inclosed path independent of said rack and pinion corresponding to the form of the rack, and means to positively direct the carrier head in said inclosed path; and a carrying arm on the said carrier head for the 80 work holder or presser foot, coacting for the purpose specified.

9. In a special work sewing machine having a suitable base, the combination of a work holder or presser foot; a main guide 85 base disposed upon the base of the sewing machine; a carrier head for traveling in the said guide base; guide members carried by said carrier head coacting with said guide base, one of which parts forms an 90 inclosed path for the other, conformed to carry the said head and positively direct the same through a predetermined course within said inclosed path; a rack and pinion means, the rack of which corresponds in 95, contour to the path of said guide parts and independent of said guides; and an arm on said carrier head to carry the said work holder or presser foot, coacting for the purpose specified.

In witness whereof I have hereunto set my hand and seal in the presence of two witnesses.

MICHAEL PETROCCHI. [L. s.]
